UNITED STATES PATENT OFFICE

172,472

HELICOPTER

Harold E. Lemont, Jr., Pottstown, Pa., assignor to
 Jacobs Aircraft Engine Company, Pottstown,
 Pa., a corporation of Pennsylvania

Application August 29, 1952, Serial No. 21,235

Term of patent 7 years

(Cl. D71—1)

To all whom it may concern:

Be it known that I, Harold E. Lemont, Jr., a citizen of the United States, residing in Pottstown, Pennsylvania, have invented a new, original, and ornamental Design for a Helicopter, of which the following is a specification, reference being had to the accompanying drawings, which form a part thereof.

Figure 1 is a side elevation of a helicopter showing my new design;

Figure 2 is a front elevation of the same;

Figure 3 is a plan view of the same;

Figure 4 is a fragmentary side view of the helicopter tail portion opposite the side shown in Figure 1.

I claim:

The ornamental design for a helicopter, as shown.
